WELL CONSTRUCTION

John R. Betts, Kearney, Nebr.

Application October 26, 1942, Serial No. 463,372

9 Claims. (Cl. 103—229)

The present invention relates to improvements in well construction and more particularly an improved foot valve and suction pipe assembly for use with pumps of very large capacity such as are required for irrigation.

An object of the present invention is to provide an improved unitary foot valve and suction pipe assembly which can be readily inserted into and removed from the well at any time.

A further object of the present invention is to provide an improved suction pipe construction in which provision is made for sealing the assembly to the rest of the well after the suction pipe has been lowered in position.

A further object of the present invention is to provide a foot valve and suction pipe assembly of extremely simple construction which can be produced from standard parts with a minimum cost.

Other objects of the invention will be apparent from a consideration of the accompanying specification, claims and drawing, in which

Figure 1 is a vertical sectional view showing one form of my suction pipe and foot valve construction, and

Figure 2 is a vertical sectional view showing a modification of my improved foot valve and suction pipe construction.

The present invention is a continuation in part of my co-pending application Serial No. 309,817, filed December 18, 1939, for "Variable capacity pumps," now Patent No. 2,299,734, issued October 27, 1942. The present application is concerned with the improved foot valve and suction pipe construction disclosed in Figure 7 of said co-pending application and originally claimed in said application. The present application is also concerned with an improved modification of this suction pipe and foot valve assembly.

Referring to the drawing for a more detailed understanding of the invention, the reference numeral 48 is employed to indicate a lining tube for the well. Welded to the lower end of the liner 48 is a ring 49, trapezoidal in cross-section. Disposed on the trapezoidal ring 49 is a gasket 50 of a rubber composition. This gasket is generally of triangular cross-section. An annulus 51 is provided with a sleeve 52 extending downwardly and screw-threadedly connected to the ring 49. The gasket 50 which is preferably of the kind known in the trade as a "Dresser gasket" is compressible by turning the annulus 51 on the ring 49 so as to screw sleeve 52 into ring 49. Extending through the sleeve 52 is the upper end of a suction pipe 56. The upper end of the suction pipe 56 is turned over to provide a flange 58 which rests on the annulus 51 to support the suction pipe and foot valve. At its lower end, the suction pipe 56 is provided with a sand screen 57. At the juncture of the conical screen 57 and the suc-

tion pipe 56 is a foot valve 59 with a guard 60 to prevent displacement of the foot valve. The foot valve 59 which is in the form of a ball is seated upon a valve seat 61 threadedly secured 5 on the collar 62 within the suction pipe 56.

The annulus 51 is provided with a bail 63 which may be grasped by any suitable tool either for turning the annulus or for hoisting the suction pipe and foot valve assembly out of the well 10 through the casing 48.

It will be appreciated from the foregoing description that the entire suction pipe and foot valve assembly can be readily removed from the well at any time by turning the bail 63 until sleeve 15 54 has become disconnected from the ring 49 and then raising the bail 63 out of the well.

The arrangement of Figure 1 is primarily designed for wells of smaller diameter. In Figure 2, I have illustrated an embodiment of my invention 20 which incorporates certain of the advantages of the species of Figure 1 but which is capable of being employed with wells of relatively large diameter, such as wells having a bore of from 10 to 32 inches in diameter.

25 Referring to Figure 2, the reference character 66 is employed to indicate a well liner corresponding to the liner 48 of Figure 1. This liner rests upon an annulus 11 which in turn is supported by a sand screen 10. Secured to the lower interior 30 portion of the liner 66 is a ring 67 of triangular cross-section. This ring is turned to conform with the shape of a "Dresser gasket" 68 of a rubber composition. The "Dresser" gasket 68 is secured over bell-shaped member 69 which is secured to a suction pipe 70 corresponding in function to suction pipe 56. A conical screen 71 is shown as secured to the bottom of suction pipe 70. It is to be understood that in certain cases this conical screen may be omitted in view of the 35 screen 10. Secured to the top of the bell-shaped section 69 is a plate 72 which is provided with a plurality of apertures with which are associated check valves 74. These valves may be of any 40 of various constructions. As illustrated, each of the valves 74 comprises a valve plate 75 slidable upon a stem 76. Each valve plate 75 is biased to closed position by a spring 77. The valves are 45 mounted within open cages 78 which allow free exit of the water passing upwardly beyond valve plate 75.

A bail 80 is secured to the plate 72 and hence to the suction pipe 70 by any suitable means of fastening such as being sealed to plate 72. It will be obvious that the entire assembly comprising suction pipe 70 and the valves 74 which function as foot valves, can be raised by raising the bail 80.

55 Due to the relatively large size of the well in which the suction pipe and foot valve construction of Figure 2 is employed, the weight of the suc-

tion pipe and foot valve assembly is sufficient to maintain the gasket 68 properly seated under normal conditions. If for some reason the valves 14 tend to stick in closed position, the entire assembly will raise off of its seat to relieve the pressure. In other words, the "dresser" gasket 68 and the ring 67 will function together as a valve to supplement the action of valves 14.

It will be seen that the arrangement of Figure 2 provides an extremely simple suction pipe and foot valve construction which permits the ready removal of the assembly with no disconnecting operation at all.

While I have shown certain specific embodiments of my invention, it is to be understood that this is for purposes of illustration only and that my invention is limited solely by the scope of the appended claims.

I claim as my invention:

1. A well and a metallic casing therefor, a ring inside said casing and welded thereto, the upper surface of said ring being downwardly and inwardly inclined, a gasket seated on said ring and having a downwardly and inwardly inclined lower surface and a flat upper surface, a hollow cylinder having an annular flat flange at the upper extremity thereof, the arrangement being such that said cylinder may be inserted through said ring with said annular flat flange seated on the flat upper surface of said gasket.

2. In combination, a well casing having a ring extending inwardly adjacent its lower end, the upper surface of said ring being downwardly and inwardly inclined, a suction pipe supported by said ring and having an enlarged upper end and a closure member for said upper end, an upwardly opening check valve secured in said closure member, and a gasket having an inclined outer face disposed between said ring and said suction pipe with the inclined surface of said gasket engaging the inclined surface of said ring and with the gasket supporting the weight of said suction pipe.

3. In combination, a well casing, a ring secured within the lower end of said casing, the upper surface of said ring being downwardly and inwardly inclined, a suction pipe supported by said ring, upwardly opening check valves associated with said suction pipe, and a gasket having an inclined outer face disposed between said ring and said suction pipe with the inclined surface of said gasket engaging the inclined surface of said ring and with said gasket supporting the weight of said suction pipe and check valves.

4. In combination, a well casing, a ring secured within the lower end of said casing, the upper surface of said ring being downwardly and inwardly inclined, a suction pipe supported by said ring, an upwardly opening check valve associated with said suction pipe, a gasket having an inclined outer face disposed between said ring and said suction pipe with the inclined surface of said gasket engaging the inclined surface of said ring and with said gasket supporting the weight of said suction pipe and check valves, and screw threaded means for compressing said gasket.

5. In combination, a well casing, a ring secured within the lower end of said casing, the upper surface of said ring being downwardly and inwardly inclined, a suction pipe supported by said ring, upwardly opening check valves associ-

ated with said suction pipe, and a gasket having an inclined outer face disposed between said ring and said suction pipe with the inclined surface of said gasket engaging the inclined surface of said ring and with said gasket supporting the weight of said suction pipe and check valves, said suction pipe and valve assembly having sufficient mass to retain themselves in operative relation on said ring.

6. In combination, a well casing, a ring secured within the lower end of said casing, the upper surface of said ring being downwardly and inwardly inclined, a suction pipe supported by said ring, upwardly opening check valves associated with said suction pipe, a gasket having an inclined outer face disposed between said ring and said suction pipe with the inclined surface of said gasket engaging the inclined surface of said ring and with said gasket supporting the weight of said suction pipe and check valves, said suction pipe and valve assembly having sufficient mass to retain themselves in operative relation on said ring without any fastening means, and a bail secured to said suction pipe for facilitating the lifting of said suction pipe and valve assembly.

7. In combination, a well casing having a ring extending inwardly adjacent its lower end, the upper surface of said ring being downwardly and inwardly inclined, a suction pipe supported by said ring and having an enlarged upper end and a flat closure member for said upper end, a circular row of upwardly opening check valves secured in said closure member, and a gasket having an inclined outer face and a horizontal upper face disposed between said ring and said suction pipe with the inclined surface of said gasket engaging the inclined surface of said ring and with the flat closure member engaging the horizontal upper face of the gasket so that the latter supports the weight of said suction pipe and check valves.

8. In combination, a well casing having a ring extending inwardly adjacent its lower end, the upper surface of said ring being downwardly and inwardly inclined, a suction pipe supported by said ring and having a projecting portion overhanging said ring, and a gasket having an inclined outer face disposed between said ring and said suction pipe with the inclined surface of said gasket engaging the inclined surface of said ring and with said gasket supporting the weight of said suction pipe, said suction pipe having sufficient mass to maintain itself in operative position on said ring without any fastening means.

9. In combination, a well casing having a ring extending inwardly adjacent its lower end, the upper surface of said ring being downwardly and inwardly inclined, a suction pipe supported by said ring and having a projecting portion overhanging said ring, a gasket having an inclined outer face disposed between said ring and said suction pipe with the inclined surface of said gasket engaging the inclined surface of said ring and with said gasket supporting the weight of said suction pipe, said suction pipe having sufficient mass to maintain itself in operative position on said ring without any fastening means, and a bail secured to the upper end of said suction pipe for lifting the same.

JOHN R. BETTS.
